Rec. 1,892.

N. B. C. Van.

Design for Angular Valve.

Patented Jan. 26, 1864.

Heads of four designs
of valves.

W. Barnet Le Van, of Philadelphia, Penn.
 Letters Patent No. 1892-Dated Jan'y. 26th 1864.
 Antedated Dec. 22nd 1863.

Design for a Valve.

The schedule referred to in these Letters Patent and making part of the same.

So all whom it may concern:

Be it known that I, Wm Barnet Le Van, of the City of Philadelphia, in the State of Pennsylvania, have invented or produced a new and original design for the form of Angular Valves; and I do hereby declare that the following is a full, clear and exact description of the same, reference being had to the Photographic view hereto annexed and making part of this specification.

The annexed Photographic view exhibits the form of valve which I have designed. The proportions of fillets between the wrench seats and the angular globe body of the valve, and between the globular body and the flange against which the face or bonnet of the valve fits, and the convex surfaces on the top and bottom of the gland nut and around the apertures in which the tubes are inserted constitute the novel and useful feature of my design.

What I claim as a new and original design and desire to secure as such by Letters Patent is, the form and proportions of the wrench seats, fillets, angular globular body and convex faces as hereinbefore described and represented.
